UNITED STATES PATENT OFFICE.

NEVIL MONROE HOPKINS, OF WASHINGTON, DISTRICT OF COLUMBIA, ASSIGNOR TO THE ELECTRIC SPEEDOMETER AND DYNAMOMETER MANUFACTURING COMPANY, OF WASHINGTON, DISTRICT OF COLUMBIA, A CORPORATION OF DELAWARE.

ATTACHMENT-PLUG FOR ENGINE-CYLINDERS.

949,704.

Specification of Letters Patent.

Patented Feb. 15, 1910.

Application filed June 23, 1909. Serial No. 503,779.

To all whom it may concern:

Be it known that I, NEVIL MONROE HOPKINS, a citizen of the United States, residing at Washington, in the District of Columbia, have invented certain new and useful Improvements in Attachment-Plugs for Engine-Cylinders, of which the following is a specification.

My invention relates to an attachment 10 plug for engine cylinders, and in particular to a construction of spark-plug, embodying features of invention applicable to spark-plugs alone, or to a combined thermo-couple and spark-plug of the kind shown in my 15 Patent No. 903,090, granted November 3, 1908.

In the drawings,—Figure 1 is a side elevation of my attachment; Figs. 2, 3, 4 and 5 are sectional elevations on the line *a—a* of Fig. 10, of modified forms of the attachment 20 plug when used as a combined thermo-couple and spark-plug; Figs. 6 and 7 are sectional elevations of the device arranged for use as a spark-plug only; Fig. 8 is a plan view of 25 the plug with the cover removed; Fig. 9 is a side elevation of Fig. 8, parts being removed to show the manner of attaching the thermo-couple; Figs. 10 and 11 are front and 30 side views of the insulating bushing and connected parts; and Fig. 12 is a vertical section of a modified construction of bushing.

The attachment plug comprises a body 2, preferably made of steel, screw-threaded at its lower portion to fit into a corresponding 35 opening in the engine cylinder, and threaded at its upper portion to engage a corresponding screw-threaded brass ring 3. The hollow porcelain cap 1 is secured to the ring 3 by bolts 22 passing through insulating bushings 70 (Fig. 9) and nuts 71 (Fig. 1), additional nuts 72 on each post serving as binding 40 screws for making electrical connection with the thermo-couple wires. The thermo-couple wires 10, 10 are secured in place by 45 means similar to those shown in my application Serial No. 445,823, filed July 28, 1908, each of these wires passing through a tube 9 of massive copper, the tubes passing through holes counterbored at their bottoms, 50 in the porcelain bushing 5. Fitting in the socket formed by the counterbore are abutments 30, preferably formed by swaging from the metal of the tubes, and between these abutments and the top of the socket is 55 a suitable asbestos packing or washer for

forming a gas-tight joint. Nuts 11 (Fig. 2), are screwed on the upper portion of the tubes, and serve to compress the packing and secure the tubes in place. At their upper ends, the tubes have stuffing-boxes 12, of 60 the construction shown in my application above referred to. These stuffing-boxes are embraced by the curved ends of plates 25 (Figs. 8 and 9), which at their other ends are secured as by soldering, to the screws 22, 65 the purpose of this arrangement being to prevent the bolts 22 from being turned about their axes by the binding nuts 72 and thus breaking the thermo-couple connecting wires 10 (Figs. 8 and 9), which are secured to the 70 bolts 22. These plates also serve to conduct the heat away from the metal inclosures of the thermo-couple wires. The thermo-couple wires are connected to each other by a junction 28.

The insulating bushing 5, which is preferably of porcelain, is secured in the body 2 by means of a screw-threaded ring 4, an asbestos packing 31 being interposed between this ring and a shoulder on the bushing, the bushing having its lower end rounded and engaging a corresponding rounded portion on the body 2. This insulating bushing 5 has, in addition to the two holes through which pass the tubes 9, 9, a third 85 hole for receiving the electrode-wire 7, which constitutes one of the spark terminals, the other terminal 8 being attached to or forming a part of the steel body 2. As shown in Fig. 2, the electrode-wire 7 is surrounded by a tube 6 of silica, quartz or porcelain, fitting into a corresponding opening in the bushing 5, there being a suitable gas-tight joint 32, of asbestos, between the bottom of the silica tube and a shoulder 90 forming part of the wall of the bushing. The wire 7 is provided at its top with a head 64, and between the head and the top of the tube is interposed a washer 63. Pressing downwardly on the head 64 of the 95 electrode-wire 7 is a spring 17, which bears also against the head of a bolt 18 held in place by a nut 38 (Fig. 1), seated in the top of the cap 1. A binding nut 34 serves as a means of making electrical connection 100 with the terminal wire 7. The pressure of this spring 17 is sufficient to firmly hold the silica tube in place and to make a gas-tight joint between the tube and bushing. The 105 use of a silica tube in this relation is par-

ticularly advantageous for the reason that the co-efficient of expansion of silica is practically *nil*, so that the tube is not liable to be cracked owing to the wide variations 5 in temperature to which the plug is subjected.

In Fig. 3 is shown a modified arrangement, the silica tube 6^a, in this case, extending entirely through the bushing 5 and being 10 below the bottom thereof. Even if the porcelain bushing should crack, the electrode-wire 7 would still be protected by adequate insulation, so that there would be no possibility of short-circuiting. Between co-operating 15 shoulders on the tube and bushing is inserted an asbestos packing 33, the tube being held in place and electrical connection made with the wire contained therein by the spring 17, arranged in the same manner 20 as described in connection with Fig. 2.

Fig. 4 shows a construction similar to that of Fig. 3 except that, in this case, the lower end of the tube is provided with a metal cap 21 to serve as an additional means for keeping 25 the joint gas-tight and for preventing the tube from splitting. Similar caps 21 may be used at the tops of the tubes if desired.

Fig. 5 shows the tube 6^b mounted in a different manner, the tube, in this case, being held up and locked to the porcelain bushing in the following manner: The electrode-wire 7 has near its lower end a shoulder 34 bearing against the cap 21 on the bottom of the tube, and at its upper end the wire 7 is threaded to receive a nut 14. Surrounding the upper portion of the tube 6^b is an insulating tube 20 bearing at its lower end on the top of the bushing 5. Between the upper 40 end of this tube and the nut 14 is a washer 13. When the nut is screwed down, it pulls up the wire 7 and silica tube 6^b and compresses an asbestos packing 36, arranged, as shown, between co-operating shoulders on the 45 tube and bushing, thereby making a gas-tight joint between the two, and also firmly fastening the parts together. A contact spring 19 serves to make the necessary electrical connection to the wire 7 and the binding screw or bolt 18.

Figs. 6 and 7 show the plug with the thermo-couple omitted, the terminal wire 7, in Fig. 6, being mounted in the same manner as before described in connection with Fig. 5; 55 the mounting of this electrode-wire in Fig. 7 being the same as in Fig. 4.

26 (Fig. 8), is a shunt wire by means of which the thermo-couple wires of each instrument can be calibrated. By adjusting 60 the conductivity of this shunt wire, the proportionate amount of current, transmitted to the indicating galvanometer, can be varied, as conditions may require.

In Fig. 12 is shown a modified construction of the bushing, which, in this case, may

be made from some insulating material such as silica or quartz, this material being directly molded or cast, while plastic or molten, about the wires, tubes or limbs passing therethrough, thus insuring a gas-tight connection between the wires, tubes or limbs and the bushing. In Fig. 12 the thermo-couple wires are shown as inclosed in metal tubes of good heat conductivity, these tubes being cast or embedded in the insulating material 75 forming the bushing so as to form a gas-tight connection therewith. A stuffing box 12 may be used if considered advisable.

I claim:—

1. A spark-plug comprising an insulating bushing, an electrode-wire passing therethrough, said bushing having an opening therethrough of different diameters, a silica tube having portions corresponding with the different diameters, a packing between the thus formed shoulders on the bushing and tube, and a spring for holding the parts in place.

2. A spark-plug comprising an insulating bushing, an electrode-wire passing therethrough, said bushing having an opening therethrough of different diameters, a silica tube having portions corresponding with the different diameters, a packing between the thus formed shoulders on the bushing and tube, a cap, and a compression spring between the cap and tube.

3. In combination, a fitting adapted to make a gas-tight joint with an engine cylinder, an insulating bushing with a longitudinal opening, an insulating tube seating in said opening, a spark electrode passing through said opening and tube, making a gas-tight joint therewith, a spring on the upper end of said tube, and an insulating top seating on said fitting compressing the spring and forcing the seated tube in position.

4. A plug comprising a body, a bushing having openings therethrough, thermo-couple tubes passing through said openings, a cap, bolts for securing the cap to the body, and plates secured to the bolts and engaging the tubes, whereby the bolts are prevented from turning.

5. In combination, a fitting adapted to make a gas-tight joint with an engine cylinder, an insulating bushing having an opening therethrough, an electrode-wire passing through said opening, an insulating tube surrounding said wire and extending into the bushing, a packing between the tube and bushing, and a compression spring arranged to bear on the end of the tube.

In testimony whereof, I affix my signature 125 in presence of two witnesses.

NEVIL MONROE HOPKINS.
